ALBERT T. MARSHALL, OF HARTFORD, CONNECTICUT, ASSIGNOR TO THE AUTOMATIC REFRIGERATING COMPANY, OF HARTFORD, CONNECTICUT, A CORPORATION OF NEW JERSEY.

AUTOMATIC SAFETY TRAP FOR REFRIGERATING MACHINES.

Application filed December 4, 1924. Serial No. 753,961.

This invention relates to refrigerating apparatus using a condensable vapor. In such apparatus trouble sometimes occurs from the passage over to the compressor of slugs of liquid which may result in the blowing out of the cylinder head or other damage. Ordinarily, the small scale trap that is interposed in the return line from the expansion coils is sufficient to intercept such slugs of liquid and hold them until they re-evaporate under the suction action of the compressor, particularly if a choke diaphragm or equivalent device is interposed in the pipe between the trap and the compressor. At other times, the amount of liquid coming over may be so great as to more than fill the scale trap.

The object of the present invention is to provide means whereby such excessive amounts of liquid will be automatically removed from the suction conduits and returned to the liquid receiver, and in the event of the liquid coming over in an amount greater than the return apparatus can take care of, I provide means whereby, in such event the compressor is automatically stopped and again started when the liquid is disposed of to a sufficient amount to make its operation safe.

The invention will be further described in connection with the accompanying drawings, in which:

Figure 1 is a diagram of refrigerating apparatus to which my invention is applied.

Figure 2 is a detail view of the switch mechanism.

Figure 3 is a detail view of a modification of part of the apparatus in section.

Figure 4 is an outside view of the top part of said modification.

A receiver 1, containing a reservoir of condensed vapor, has a pipe 2 leading to an expansion valve which feeds the expansion or refrigerating coils. A return pipe 3 from the expansion coils leads to the suction of a compressor 4 and a pipe 5 takes the compressed vapor from the compressor to the condenser 6. A scale trap 7 is interposed in the suction line and at 8 may be introduced a choke diaphragm in which the vapor is compelled to pass through an orifice very much smaller than the cross section of the pipe 3, with the result that any slugs of liquid passing through will be held up and only so much allowed to pass as the compressor can take care of. A back pressure switch is shown at 9, which serves the usual purpose of stopping the compressor when the pressure in the suction line falls below a certain limit, and restarting the compressor when the said pressure returns to a predetermined point. When larger amounts of liquid come over than the scale trap can take care of, I provide means whereby the surplus liquid can be automatically drained away as follows:

A drain pipe 10 from the scale trap discharges the liquid from the scale trap into a safety trap 11 which is of ample size to take care of such excessive amounts of liquid. A pipe 12 leads from the bottom of the safety trap to a pump 13 which pumps the liquid from the safety trap through pipe 14 to, for example, the receiver 1. The safety trap 11 should be surrounded with cork or other heat insulation 15 and is shown mounted on the platform of a weighing scale 16, the weight beam 17 of which has the usual adjusting weights 18 held on its outer end. Mounted on a stationary support is an electric switch 19 which may be of the usual quick-acting, snap-over type. It is operated by a rod 20 which impinges against the scale beam 17, against which it is held either by its own weight or by weight assisted by the spring 21. Adjustable stops 22 on the rod determine accurately at what point the said stops actuate the trigger 23 that, by means of spring 24, acts to throw the switch 19 either up against contact 25 or down against rest 26. From contact 25 and switch 19, circuits lead to the motor driving the liquid pump 13. In addition to the adjustable weights 18 on the scale beam, I provide an additional weight 27 held normally suspended on supports 28 from the frame. An adjustable piece 29 on the weight rod 30 is adapted to lift the weight 27 and transfer its weight from supports 28 to the rod 30 when the weight of the liquid accumulated in the safety trap exceeds a certain amount. Before this occurs, the scale beam will have moved enough in response to the accumulated weight in the safety trap to operate the switch 19 and start the liquid pump pumping liquid from the safety trap to the receiver. Should, however, the liquid continue to increase faster than the pump can take care of it, the weight so accumu-

lated will tip the scale beam still further and cause the member 29 to lift the weight 27. When this occurs, the scale beam going up still further, will lift operating rod 31 of an additional switch 32. This switch may be a quick-acting switch as is the switch 19. When the rod 31 is thus pushed up by the scale beam, the switch 32 breaks the circuit 38 of the motor driving compressor so that the compressor will be stopped before any damage from further accumulation of liquid may occur. While I have shown these electric switches 19 and 32 as being placed directly in the circuits of the motors, they are, in practice, preferably of the relay type and only operate circuits of small current value that control electromagnetic main switches in the motor circuits in a manner well understood in the art. It is, of course, understood that pipes 10 and 12 supplying liquid to and from the safety trap, will be flexible enough to permit the free vertical motion of the trap. As the total vertical motion of the trap is a small fraction of an inch, this does not require any special provision in the pipe although such special provision may, of course, be made. The safety trap just described, thus serves to trap a certain amount of liquid, which may be re-evaporated by the suction of the pump without actuating the weighing mechanism. Should it, however, accumulate faster than the compressor can take care of it, it will, after arriving at a certain level, cause, by its weight, an initial movement of the scale-beam whereby the weights 18 are lifted until the member 29 rests against the weight 27. At this point, the liquid pump 13 will be started and ordinarily will soon empty the safety trap. When the trap is sufficiently evacuated, the weight 18 will again descend, which will result in the opening of the circuit of the motor driving the liquid pump, thus causing a cessation of the operation of the pump until the liquid again accumulates. Should, however, the accumulation of liquid continue at a rate that the small pump 13 is not able to take care of, the added weight in the trap will cause a further movement of the scale-beam whereby member 29 will be enabled to lift the weight 27 and this will cause the operation of the switch 32 and shut down the compressor. The compressor may subsequently be started up again by the operator, or, if desired, the compressor may be automatically restarted by the closing again of the circuit of its driving motor, when the evacuation of the trap by the liquid pump brings the weight of liquid in the trap down to a point where it would be safe for the compressor to again start the suction.

In Figure 3 I have shown another way of accomplishing the same result. Here a stationary trap 34 has a float 35 which is sup-

ported on a spring 36. This float moves freely within the trap up and down and, by means of connecting link 37 and bell crank 38, operates a rock shaft 39 that, passing through a stuffing box, has on its outer end a switch arm 40 (see Figure 4) that operates between contacts 41 and 42, which may be the relay contacts for a main switch controlling the motor driving the liquid pump or the motor driving the compressor, or, as shown in connection with the weight trap, there may be two such switches, one operating first to start the pump and the other following upon further accumulation of liquid, to stop the compressor. While I have shown two means of carrying my invention into effect, I do not wish to be limited specifically thereto, as there are alternative means that could be equally applicable. The liquid pump could be started and stopped by mechanical means instead of electrical and the trapped liquid may be returned to any part of the system suitable to receive it. In some cases this might be part of the expansion side, like coils or cooler in large brine tank. For causing the weight of liquid in the trap to operate the switches, I have shown an ordinary form of platform weighing scale but the same result could be obtained if the trap were suspended by suitable levers that would give the desired multiplied motion. The scale trap can be omitted and safety trap serve the purpose of both. The action of the accumulation of liquid in the trap 11 in operating the switches to start and stop the motors requires a certain amount of time. In other words, it is necessary that the scale beam does not move quickly from one position to another but that its action be delayed in order that the trap may have time to fill or empty as the case may be, so as to not have the starting and stopping of the motors occur more often than necessary. This delayed action may, for example, be brought about by the tension of the springs 24 of the electric switches acting to hold in restraint the rod 20 until the maximum and minimum weights in the trap are reached. In the same way, the spring 24 of the switch 32 will restrain the operation of rod 31 until the desired additional accumulation or reduction of liquid in the trap takes place. A spring 43 whose tension is adjustable by means of an adjusting screw 44, may be used to regulate the resistance to the movement of the scale beam under the action of the liquid in the trap. In Figure 2 I have shown in a dotted line diagram, means whereby the movement of the scale lever acting under the combined effect of the changeable weight of the liquid trap, the weights 18 and 27, and the spring 43, may act to close and open relay circuits from a source of electricity, shown at 45, whereby

a contact arm 46 will contact with terminals 47 and 48 near the lower and upper limits of the motion of the scale beam, to operate a throw-over switch 49 by means of electro-
 5 magnets 50 and 51, to open the circuit of the liquid pump motor when the scale beam is near its lowermost position, and to close the same when the scale beam is near its uppermost position. It will be noted that
 10 such a switch operates only when the scale beam nears its extreme position and is inactive at intermediate points. Similarly, the contact 46 may at lower and higher elevations of the scale beam, make contact
 15 with terminals 52 and 53, which, operating through electromagnets 54 and 55, will control a switch 56 that will operate at the proper times to close or open the circuits 33 of the motor driving the compressor. It
 20 will be understood that with such switches, the scale control spring 43 will keep the scale resistance to the weight of the liquid in the trap in balance, which, in the ordinary operation of the plant, will mean that
 25 the liquid pump is not running and the compressor is running, the fluctuations of liquid in the trap, if any, being not sufficient to cause the contact 46 to reach any of the terminals. Should, however, the accumulation of liquid in the trap become suffi-
 30 ciently great to overcome the forces holding down the scale beam to such an extent as to cause contact 46 to reach terminal 48, the switch 49 will close the circuit of the motor driving the liquid pump and thus start the evacuation of the trap, returning the liquid therein to the receiver or any other suitable location. Ordinarily the operation of the liquid pump will prevent further accumulation of liquid in the trap and decrease the same until the trap is nearly or quite empty when contact 46 will touch terminal 47 and open the circuit of the liquid pump motor. If the operation of the pump is not sufficient to take care of the accumulation of liquid in the trap, the scale beam will lift still further and when contact 46 touches terminal 53, the magnet 55 will operate switch 56 to open the circuit 33 of the compressor motor, thus shutting down the compressor before damage can be done by overflow of liquid into the compressor cylinders. With the compressor thus shut down, the pump will be enabled to evacuate the trap
 55 and at some suitable point in the descent of the scale beam consequent thereupon, the contact 46 will touch terminal 52 and restart the compressor by the operation of magnet 54 closing switch 56. From there on the compressor will ordinarily take care of further accumulations but the liquid pump will continue to operate until contact 46 reaches terminal 47 when the trap being emptied, the pump motor will be stopped.
 60 It will be seen from the above that I have
 65

provided means whereby abnormal accumulation of liquid in the trap will start a pump or other means which may, of course, be a release valve to bring about the reduction of the accumulation and that upon still further accumulation beyond the ability of such means to take care of, still other means are provided for, in that event shutting down the compressor and that upon the reduction of the weight of liquid in the trap to a desired minimum, these operations are reversed.

I claim:—

1. The method of preventing excessive amounts of liquid from entering the suction of the compressor of a refrigerating system, which consists in running such excessive liquid into a trap and causing the accumulation of weight of the liquid in the trap to operate electric switches to start a pump that will evacuate the trap when the accumulation of liquid in the trap exceeds a certain amount and upon the further accumulation of liquid in the trap to stop the compressor and again start the compressor when the liquid in the trap is reduced a predetermined amount.

2. In a refrigerating system using a condensable vapor, the combination comprising a compressor having suction and delivery pipes, a trap for liquid in the suction pipe, means operated by the weight of accumulated liquid in the trap to force the liquid from the trap into the delivery pipe, and other means for stopping the compressor upon further accumulation of liquid in the trap.

3. In a refrigerating system using a condensable vapor, the combination comprising a compressor having suction and delivery pipes, a trap for liquid in the suction pipe, means operated by the weight of accumulated liquid in the trap to force the liquid from the trap into the delivery pipe, other means for stopping the compressor upon further accumulation of liquid in the trap, and means for restarting the compressor when the weight reduces.

4. In a refrigerating system using a condensable vapor, the combination comprising a compressor having suction and delivery pipes, a trap for liquid in the suction pipe, means operated by the weight of accumulated liquid in the trap to force the liquid from the trap into the delivery pipe, other means for stopping the compressor upon further accumulation of liquid in the trap, and means for restarting the compressor when the weight reduces and stopping the liquid pump upon still further reduction of weight.

5. In a refrigerating system using a condensable vapor, the combination comprising a compressor having suction and delivery pipes, a trap for liquid in the suction

pipe, means operated by the weight of accumulated liquid in the trap to force the liquid from the trap, and means for opposing a cumulative resistance to the weight operated means to delay the action of the said weight operated means until a desired maximum accumulation has been reached.

6. In a refrigerating system using a condensable vapor, the combination comprising a compressor having suction and delivery

10 pipes, a trap for liquid in the suction pipe, means operated by the weight of accumulated liquid in the trap to force the liquid from the trap, and adjustable means for opposing a cumulative resistance to the weight operated means to delay the action of the said weight operated means until a desired maximum accumulation has been reached.

ALBERT T. MARSHALL.
